UNITED STATES PATENT OFFICE.

WILLIAM M. HAND, OF ST. LOUIS, MISSOURI, ASSIGNOR TO THE GENERAL ELECTRIC COMPANY, OF NEW YORK.

BRUSH-HOLDER FOR DYNAMOS.

SPECIFICATION forming part of Letters Patent No. 569,824, dated October 20, 1896.

Application filed January 27, 1896. Serial No. 576,944. (No model.)

To all whom it may concern:

Be it known that I, WILLIAM M. HAND, of the city of St. Louis, State of Missouri, have invented a certain new and useful Improvement in Brush-Holders for Dynamos, of which the following is a full, clear, and exact description, reference being had to the accompanying drawings, forming part of this specification.

10 My invention relates to an improved construction whereby the pressure of the brushes on the commutator of the dynamo may be regulated quickly and with accuracy, and the tension can be readily examined to ascertain 15 if an adjustment is required.

My improved construction of holder provides, further, for a free and unobstructed flow of the electric current through the holder, whereby resistance and consequent heating 20 of the holder and brushes is avoided.

My invention consists in features of novelty hereinafter fully described, and pointed out in the claims.

Figure I is a top or plan view of my improved holder. Fig. II is a section taken on line II II, Fig. I. Fig. III is a top or plan view of one of the brushes removed. Fig. IV is a section taken on line IV IV, Fig. III. Fig. V is an edge view of one of the brushes re- 30 moved and showing the carbon of the brush as having a concave face or end. Fig. VI is an end view of the carbon shown in Fig. V.

Referring to the drawings, 1 represents the head of a brush-holder, which is provided with 35 any suitable means 2 for support. The head has one or more sockets 3, in which the brushes fit. I have shown the head provided with two of these sockets, each adapted to contain a brush. 4 represents part of the commutator 40 of a dynamo, against which the carbons 5 of the brushes are adapted to bear. Each carbon is secured to a block 6. The connection may be made by forming a socket 7 in the block to receive a shank 8 on the carbon, as 45 shown in Figs. II and III. The shanks 8 are held in the sockets by solder 8^a, which not only forms a secure attachment of the carbons to the block, but produces an excellent electric contact between the two, and to still 50 further improve this union I form holes 8^b

in the neck 8, which become filled with the solder.

9 represents a plate having an outwardly-extending handle 10 and an inwardly-extending projection 11. The plate 9 is of such size 55 as to fit snugly in its socket 3 of the head 1, and the projection 11 is of such width as to snugly fit between the bottom and top walls of the socket. The plate 9 is connected to the block 6 by means of serpentine ribbon- 60 springs 12, one fitting on each side of the projection 11, as shown in Fig. III.

13 represents a stem made fast to the block 6 and which passes loosely through the projection 11 and handle 10 of the plate 9. The 65 stem is provided with a button 14 on its outer end. The head 1 is provided with a set-screw 15 over each socket 3, the set-screws passing through the top of the head, as shown in Fig. II.

When the brushes are inserted, the set-screws 15 are tightened down, the lower ends of the set-screws jamming against the upper faces of the projections 11. The plates 9 are thus clamped in the head by means of the set-screws, and the carbons are held against 70 the commutator by the springs 12. By taking hold of the buttons 14 on the stems 13 an experienced person can readily judge as to whether or not the carbons are held with the desired amount of force against the commu- 75 tator, and if he finds the force is more than it should be he simply loosens the screws 15, and by taking hold of the handles 10 draws the plates 9 farther out in the head 1, and then tightens the set-screws again. If he 80 finds that the carbons are not held against the commutator with sufficient pressure, he loosens the set-screws and forces the plates 9 farther into the head 1 and again tightens the set-screws. As the carbons wear away 85 they can be readily examined as to their ten- 90 sion or pressure against the commutator and when necessary can be quickly and effect- 95 ively adjusted by the set-screws bearing on the long projections 11, as explained.

Inasmuch as the plates 9 and projections 11 fit snugly in the sockets of the head 1 and are clamped in close bearing with the head by the set-screws and inasmuch as the serpentine ribbon-springs form an electric connection 100

between the block 6 and the head 1 through the plates 9 and projections 11 of large current-conducting capacity there is no danger of the heating of the parts and the consequent loss of current and carbon.

I claim as my invention—

1. In combination with a commutator-brush and a holder therefor having a socket; a spring for pressing the brush and conducting the current, working in said socket and formed of flat metal having its transverse dimension in the direction of yielding reduced to give the requisite resiliency and having its other transverse dimension relatively increased to afford ample section for conductivity without heating, as herein explained.

2. In combination with a commutator-brush holder having a socket; a spring working in said socket for pressing the brush and conducting the electric current, formed of metal having its transverse dimension in the direction of yielding reduced to give the requisite resiliency and having its other dimension increased to afford ample section for conductivity without heating, said spring being formed by bending the metal backward and

forward upon itself in serpentine form, substantially as herein explained.

3. In a brush-holder, the combination of a head having a socket, a block fitting in the socket and adapted to carry a carbon, a plate fitting in the socket and having an inwardly-extending projection and an outwardly-extending handle, a set-screw fitting in the head and adapted to bear against said projection, springs connecting said block to said plate, and a stem connected to said block and passing loosely through said projection and said handle, substantially as and for the purpose set forth. 40

4. In a brush-holder, the combination of a block having a socket, and a carbon having a neck fitting in the socket and held therein by solder, substantially as set forth.

5. In a brush-holder, the combination of a block having a socket, and a brush having a perforated neck fitting in said socket and held therein by solder, substantially as set forth. 45

WM. M. HAND.

In presence of—
E. S. KNIGHT,
W. FINLEY.
